UNITED STATES PATENT OFFICE.

CLARENCE R. WELCH, OF ROSSLAND, BRITISH COLUMBIA, CANADA.

GOVERNOR ATTACHMENT.

No. 832,846.

Specification of Letters Patent.

Patented May 26, 1908.

Application filed July 18, 1907. Serial No. 382,416.

To all whom it may concern:

Be it known that I, CLARENCE R. WELCH, a citizen of the United States, residing at Rossland, in the Province of British Columbia and State of Canada, have invented new and useful Improvements in Governor Attachments, of which the following is a specification.

This invention relates to governor attachment, particularly adapted for use in connection with winding engines; and the object thereof is to provide in a manner as herein-after set forth an attachment for use in connection with a governor for throwing into operation the controlling device of the engine to reduce the speed of the latter should the speed be excessive.

Although the attachment is designed primarily for use in connection with winding engines, yet its use is not limited in such particular as it is adapted for any purposes for which it is found applicable.

Further objects of the invention are to provide an attachment for use in connection with a governor for the purpose set forth which shall be simple in its construction, strong, durable, efficient in its use, automatic in its operation, readily set up with respect to the engine and its controlling means, and comparatively inexpensive to manufacture.

With the foregoing and other objects in view the invention consists in the novel features of construction, combination and arrangement of parts hereinafter more specifically described and illustrated in the accompanying drawings wherein is shown the preferred embodiment of the invention, but it is to be understood that changes, variations and modifications can be resorted to which come within the scope of the claims hereunto appended.

In describing the invention in detail reference is had to the accompanying drawings wherein like reference characters denote corresponding parts throughout the several views, and in which—

Figure 1 is a front elevation, and Fig. 2 a side view of an attachment for use in connection with a governor in accordance with this invention.

Referring to the drawings by reference characters, 1 denotes centrifugal spherical bodies, suspended on the arms 2 which are pivoted to the head 3 fixed on the shaft 4, this shaft receiving motion from the engine

in a known manner. Upon the shaft 4 is mounted a sliding collar 5 connected to the arms 2 by the straps 6. These latter are pivotally connected to the arms 2, as at 7. The collar 5 is grooved as at 8, and, engaging therein is the forked end 9 of the lever arm 10, the latter being fixed to a rock shaft 11. Depending from the rock shaft 11 and fixed at its upper end thereto is a lever arm 12 carrying on its lower end a roller 13. In lieu of providing two separate levers 10 and 12 fixed at their upper ends to the shaft 11 a bell-crank can be employed which is loosely mounted upon the shaft 11. As this construction is obvious it is thought unnecessary to show it as the levers 10, 12, owing to their arrangement, constitute the bell-crank.

The reference characters 14, 15 denote a pair of sprocket wheels, one arranged above the other, each rotatably connected to a shaft 16 and receiving motion from the engine in any suitable manner, preferably by gearing. The reference character 17 denotes a sprocket chain engaging with the sprocket wheels 14, 15, these latter transmitting motion to the chain 17. As the sprocket wheels 14, 15 receive motion from the engine the travel of the chain always bears a certain relation to the movement of the engine or the position of the load when winding. The relation is such that the chain does not make more than one revolution during the greatest distance the load is wound. The chain 17 is arranged in suitable relation with respect to the lever arm 12 so that the roller 13 will bear against the chain 17, the roller being positioned within the chain and bearing against the inner face of one side thereof. The chain 17 carries a trip member 18 so positioned on the chain that when the engine starts to rotate at an excessive speed the said member 18 will engage a controlling device and shift it into operation, consequently slackening the speed of the engine or discontinuing the operation of the latter. By way of example a lever arm 19 is shown, which is attached through the medium of the link 20 to the controlling valve of the engine. One end of the lever arm 19 is adapted to extend in the path of the member 18 when the engine is running at an excessive rate of speed. This action is had owing to the fact that the side of the chain carrying member 18 is deflected to the left through the medium of the roller 13.

Such provision positions the member 18 in such a manner that as it moves upwardly it

will engage the lever 19 and operate the controlling valve so as to decrease the speed of the engine or discontinue the operation thereof.

5. The operation of the attachment is as follows: It will be assumed that the member 16 is positioned at what may be termed the danger point. Now if the arms 2, which carry the spherical bodies 1, are elevated 10 through the medium of centrifugal force, the straps 6 will be carried with the arms, causing a vertical shifting of the collar 5 upon the shaft 4 and owing to such movement of the collar 5 the forked end of the lever 10 will be 15 elevated, such action rocking the shaft 11 which will cause the moving of the lever 12 to the left, the lever 12 carrying the roller 13 therewith and as the latter abuts against the chain 17 the left side of the chain will be deflected so as to position the member 18 under the free end of the lever 19. As the member 20 18 moves vertically it engages the lever 19 and shifts it, thereby throwing the controlling valve into operation.
- 25 It is evident from the foregoing operation that the governing of the speed of the engine is had in an automatic manner.

What I claim is—

1. A governor attachment for the purpose 30 set forth, comprising an endless carrier, means for imparting movement thereto, shiftable means for actuating the engine controlling mechanism, a trip member attached to said carrier and adapted to be moved to a

position to actuate said shiftable means, an oscillatory lever mechanism adapted to engage said carrier and shift a portion thereof, thereby positioning said member to engage said shiftable means, means controlled by the speed of the engine for oscillating said lever mechanism.

2. A governor attachment for the purpose set forth comprising an endless carrier, means driven from the engine for actuating said carrier, a shaft, a sliding collar having 45 its movement controlled by the speed of the engine, a lever arm fixed at one end to said shaft and its other end engaging said collar, said collar during its movement shifting said lever arm, thereby rocking said shaft, a lever arm fixed at one end to said shaft and carrying at its other end a roller adapted to engage said carrier when the shaft is rocked to deflect a portion of the carrier, a shiftable means for actuating a controlling device, and a trip member attached to the carrier and adapted when a portion of the carrier is deflected to be positioned to engage and actuate said shiftable means during the travel of the carrier.

In testimony whereof I have hereunto set my hand in presence of two subscribing witnesses.

CLARENCE R. WELCH.
